UNITED STATES PATENT OFFICE.

MAGNI GUSTAFSON FRÖBERG, OF LILLA ESSINGEN, STOCKHOLM, SWEDEN.

SUSPENSION DEVICE FOR PICTURES OR OTHER OBJECTS.

1,115,800.

Specification of Letters Patent.

Patented Nov. 3, 1914.

Application filed July 29, 1912. Serial No. 711,984.

To all whom it may concern:

Be it known that I, MAGNI GUSTAFSON FRÖBERG, a subject of the King of Sweden, and resident of Lilla Essingen, Stockholm,

5 Sweden, have invented certain new and useful Improvements in Suspension Devices for Pictures or other Objects, of which the following is a specification, reference being made to the accompanying drawing.

10 The present invention relates to devices for suspending pictures or other objects, which devices—as already known—consist of a piece of wire, one part of which wire forms a pin, intended to be driven into a wall or the like, while another part of the piece of wire forms a hook (or hooks), or the like. A suspension device carried out in accordance with the present invention is characterized mainly by the fact, that a part of 15 the wire, situated between the pin and the hook, is passed one or more times over the pin, whereby a strengthening of the device is attained.

20 In the accompanying drawing are shown by way of example two different forms of the present invention.

25 Figures 1 and 2 show one construction, seen from one side or from the front respectively, while Fig. 3 shows the other construction, seen from one side.

30 The suspension device shown in Figs. 1 and 2 consists of a piece of wire, one end of which wire is pointed, so that one end part of the wire forms a pin 1, intended to be driven into a wall 2 or the like. The pin continues with a bent part of the wire in a part 3, which, when the device is fixed in a wall, extends downward and inward toward the wall, and the said part 3 continues 35 with a bending of the wire in a part 4, which extends upward along the wall on one side of the pin 1 inserted in the wall. With a part 5 of the wire bent over the pin the part 4 continues in a part 6, which extends downward along the wall on the other side of the pin, and which part 6 forms the shank of the hook 7 of the bearing device. The part 5 of the wire, which is passed over 40 the pin, should preferably rest upon the pin, whereby is attained the advantage that the 45 load on the hook is transferred as directly

as possible to the pin (and thus to the wall), the pin being driven into the wall so far that the part 5 is brought to rest against the said wall.

55

When the device is fixed into a wall, one should take care that the parts 4 and 6 rest against the wall, as shown in Fig. 1. When the hook is loaded with *e. g.* a slanting picture, it yields or springs out from the wall. 60 This springing movement is rendered possible by the bent transitions between the hook and the pin.

65 In the form shown in Fig. 3, each of the end parts of the wire forms a pin 1 and 1^a respectively. When the device is fixed in a wall, the pins 1 and 1^a lie in the same vertical plane. The part of the wire situated between the two pins forms two hooks 7 and 7^a (suitable for suspending *e. g.* a hat and 70 coat), and the part 5 which continues in the hook shank 6 is carried several times over the pin 1, forming a winding around it. It will be noted from an inspection of the drawing that the loop which surrounds 75 the slanting pin portion is disposed at an angle thereto but in a plane parallel with the plane of the support. As the pin is driven into the support this loop will be slid upwardly upon the pin for binding engagement therewith, and by its resiliency 80 will also be forced into engagement with the support, thereby holding the pin against rotation which might serve to cause the displacement of the device.

85

Suspension devices carried out according to the present invention are very cheap to manufacture.

Having now described my invention, what I claim as new and desire to secure by Letters Patent is:

90 As a new article of manufacture, a supporting device for pictures or the like comprising a single strand of wire having a downwardly inclined pin formed at one end 95 thereof and adapted for insertion into the support, a hook provided at one end of the strand and having a straight side adapted to engage the adjacent portion of the support, and a loop formed upon the shank between the pin and the hook and surrounding the pin at its upper end for sliding move-

100

ment thereon, said loop being disposed at an oblique angle relative to the pin and in a plane parallel to the adjacent side of the support, whereby when pressure is exerted upon the hook the loop will be slid downwardly upon the outer end of the pin and forced into binding engagement with the said outer end of the pin and the adjacent

portion of the support for holding the hook against rotation.

10

In witness whereof I have hereunto set my hand in presence of two witnesses.

MAGNI GUSTAFSON FRÖBERG.
